UNITED STATES PATENT OFFICE.

GWILYM M. WILLIAMS, OF WILKES-BARRÉ, PENNSYLVANIA.

ALARM.

SPECIFICATION forming part of Letters Patent No. 409,088, dated August 13, 1889.

Application filed February 4, 1889. Serial No. 298,624. (No model.)

To all whom it may concern:

Be it known that I, GWILYM M. WILLIAMS, a citizen of the United States, residing at Wilkes-Barré, in the county of Luzerne and State of Pennsylvania, have invented certain new and useful Improvements in an Electric Alarm Attachment for Pressure-Gages, of which the following is a specification.

This invention relates to an electric alarm attachment for pressure-gages, and is designed especially for use upon gages of that class embodying an oscillating or partially-rotatable indicator.

The object of the invention is to provide a device of this character adapted to sound an alarm when the pressure passes beyond a desired limit, whether it be greater or less than said limit.

A further object of the invention is to provide means for adjusting the device to regulate the points at which the alarm may be sounded.

A further object of the invention is to provide an electric alarm attachment of this character adapted to be thrown in or out of operation, as desired.

A further object of the invention is to provide a simple and improved electric alarm of this class which will possess advantages in point of inexpensiveness, durability, and general efficiency.

In the drawings, Figure 1 is a perspective view of a pressure-gage, showing my electric alarm attachment applied thereto. Fig. 2 is a side elevation illustrating the circuit-closer thrown out of operation. Fig. 3 is a top or plan view. Figs. 4 and 5 are detail sectional views at right angles to each other, taken through the circuit-closer and adjacent parts of the gage, the latter view illustrating the manner of insulating the circuit-closer. Fig. 6 is a detail perspective view of the circuit-closer. Fig. 7 is a detail perspective view of a modification.

Corresponding parts in the figures are denoted by the same letters of reference.

The present invention is herein shown as applied to my newly-invented pressure-gage, for which application was filed November 15, 1888, Serial No. 290,891. The latter comprises, briefly, a casing A, provided with a

pressure-actuated diaphragm, (not shown,) and a casing B, mounted upon the top *a* of the casing A. A shaft C is mounted in the casing B and projects therefrom, said shaft being connected with the diaphragm by suitable mechanism, and is oscillated by the movement of the diaphragm. Upon the outer end of the shaft is mounted an indicator *c*, or a recording-arm, (illustrated in Fig. 7,) adapted to carry a pen or pencil for recording the pressure and time upon a chart provided therefor,

Upon the top of the casing is secured my improved circuit-closer D, a plate E, of hard rubber or other insulating material, being interposed between the two. This circuit-closer comprises a plate *d*, preferably secured to the gage by screws passed through perforations *d*' *d*" provided therefor in said plate. The screws are insulated by blocks *d*² *d*²', also preferably of hard rubber and having reduced cylindrical portions, which project through the perforations *d*', said blocks being each provided with perforations through which the securing-screws pass. Complete insulation between the circuit-closer and gage is thus secured.

To the rigid plate *d* is hinged a plate F, which, when the alarm mechanism is in use, rests upon the plate E, the latter being of sufficient size to accomplish this purpose. The plate F is provided at its ends with corresponding upwardly-projecting lugs *f* *f*', having horizontal oppositely-disposed screw-threaded perforations *f*' *f*" for the reception of adjustable opposing thumb-screws G G, the inner opposing ends of which are preferably pointed, as shown.

H designates a plate, preferably formed of spring metal, which projects downwardly from the indicator *c*, or from the shaft C, and between the opposing ends of the screws G G. This plate is carried by the shaft in its movement, and has free play within the limit allowed by the adjusting-screws. By reason of its spring action, when the plate comes in contact with one of the screws, it yields to further pressure in that direction, but remains in contact with the screw.

Upon the gage and plate are disposed binding-posts I I, of any suitable construction, which are connected by wires in the usual manner with a battery J and with a bell K or

other alarm mechanism. In addition to the bell K, I prefer to employ one or more bells L, situated at desired points and connected with the poles of the battery by branch wires.

5 By the employment of this additional alarm mechanism, should the circuit through any of the bells become broken the remaining ones will sound an alarm.

The operation and advantages of my invention will be readily understood by those skilled in the art to which it appertains. The degree of pressure above or below the normal or average pressure at which it is desired to have the alarm sounded is regulated by the adjustment 15 of the thumb-screws. When the pressure becomes greater or less than the limit to which the screws have been adjusted, the plate II comes in contact with one of the screws, which forms a complete circuit through the gage 20 and circuit-closer, and an alarm will be sounded until the pressure becomes greater or less, as the case may be, and the contact of said plate and the screw is broken.

When an operation of the gage is desired 25 independent of the alarm, the plate F is thrown back, removing the circuit-closer from any possible contact with the plate II.

I claim as my invention—

1. In an electric alarm for pressure-gages, 30 the combination, with a rigid plate, of a plate hinged thereto, provided with upwardly-projecting corresponding lugs disposed at each end thereof, and having opposing contact-points, substantially as and for the purpose set forth.

2. In an electric alarm for pressure-gages, the combination, with a rigid plate, of two corresponding lugs pivotally connected therewith and provided with opposing adjustable screws forming contact-points, substantially 40 as and for the purpose set forth.

3. The combination, with a pressure-gage provided with an oscillating indicator-shaft and a plate projecting downwardly from the latter, of an insulated circuit-closer comprising a rigid plate, lugs pivotally connected therewith, projecting at each side the downwardly-projecting plate and provided with contact-points for engagement by the latter, said circuit-closer being adapted to be thrown 50 in or out of operation, and battery and alarm mechanism connected by wires with the shaft and circuit-closer, substantially as set forth.

4. The combination, with a pressure-gage provided with an oscillating indicator-shaft 55 and a plate projecting downwardly from the latter, of an insulated circuit-closer comprising a rigid plate and a plate hinged thereto provided with two corresponding lugs projecting at each side the downwardly-projecting plate, opposing adjustable screws provided through the lugs, and battery and alarm mechanism connected by wires with the shaft and circuit-closer, substantially as set forth.

In testimony whereof I affix my signature in 60 presence of two witnesses.

GWILYM M. WILLIAMS.
